(57) **CLAIM**

We claim the ornamental design for a “bottle holder”, as shown and described.

DESCRIPTION

FIG. 1 is a front perspective view of a bottle holder showing our new design;

FIG. 2 is a right side perspective view thereof, the left side being a mirror image;

FIG. 3 is a top plan view thereof;

FIG. 4 is a rear perspective view thereof;

FIG. 5 is a front perspective view of an alternate embodiment of FIG. 1;

FIG. 6 is a right side perspective view of FIG. 5, the left side being a mirror image;

FIG. 7 is a top plan view of FIG. 5; and,

FIG. 8 is a rear perspective view of FIG. 5.

The broken lines are for illustrative purposes only and form no part of the claimed design.
